SPRING LINER

Gustav Walters and Ernest F. Gatzke, Middletown, Conn., assignors to The Russell Manufacturing Company, Middletown, Conn., a corporation of Connecticut

Application October 3, 1949, Serial No. 119,326

20 Claims. (Cl. 267—47)

1

The present invention relates in general to fabrics and more especially to an improved method and means for manufacturing an embossed fabric for use as a spring-liner.

An object of the invention is to provide a woven fabric with an integral woven boss.

A further object of the invention is to provide a fabric spring-liner having a superior boss formed thereon.

A still further object of the invention is to provide a woven multi-ply fabric having integrally-woven bosses on one face of the fabric arranged in spaced relationship longitudinally thereof.

A still further object of the invention is to provide a superior woven spring-liner fabric having bosses formed integral therewith of a plurality of closely-arranged upstanding loops of the woven fabric.

A still further object of the invention is to provide a substantially-incompressible woven-fabric spring-liner having an integrally-woven boss projecting upwardly from one face thereof.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a plan view of a fragment of the embossed woven spring-liner fabric of this invention;

Fig. 2 is a side elevation of the fabric of Fig. 1;

Fig. 3 is an end elevation in section on line 3—3 of Fig. 1;

Fig. 4 is an end elevation on section-line 4—4 of Fig. 1;

Fig. 5 is an enlarged broken longitudinal section on line 5—5 of Fig. 1 illustrating the arrangement of the warps and wefts of the two-ply fabric and in particular the formation of the woven fabric bosses;

Fig. 6 is a broken transverse section of the fabric on line 6—6 of Fig. 5 showing details of the arrangement of the warp and weft strands of the upper and lower plies and the formation of a boss on the upper ply;

Fig. 7 is a schematic showing of a pick schedule illustrating the sequence of shedding operations and picks of the weft for forming the embossed fabric but with the lower ply warps omitted;

Fig. 8 is a plan view of a spring-liner member

2

formed from fabric cut from a length of embossed fabric such as shown in Fig. 1;

Fig. 9 is an edge elevation of the spring-liner member of Fig. 8;

Fig. 10 is a schematic elevation of an automobile spring showing spring-liners mounted between the superposed leaves of the spring, adjacent the outer ends thereof;

Fig. 11 is a plan view of a modification of the embossed spring-liner fabric of Fig. 1;

Fig. 12 is a schematic plan view of a short length of a further modification of the embossed spring-liner fabric of Fig. 1 showing the use of double-stranded wire ends in the fabric;

Fig. 13 is a schematic plan view of the bottom of the fabric of Fig. 12; and

Fig. 14 is an enlarged fragmentary sectional view of the fabric on line 14—14 of Fig. 12 showing the wire ends in both the upper and lower plies of the fabric.

The embossed fabric of this invention is particularly suitable as a lining material to be used between the leaves of automobile springs to prevent squeaking, and to this end is preferably a two-ply fabric woven of relatively heavy cotton strands. Moreover, as an alternate construction, it is proposed to weave wire into the embossed fabric, as hereinafter described, to form a fabric of low compressibility and great durability. It will be understood, however, that it is within the purview of the invention to form the embossed fabric of other materials and as a single- or double-ply fabric.

The showings of Figs. 1 through 10, inclusive

Referring to the drawings, the double-ply embossed spring-liner fabric, indicated generally at 15, is woven in the form of a continuous web or tape, the width of which corresponds substantially to the width of a leaf spring of an auto; and woven integrally with the upper surface of the web 15 are a plurality of bosses indicated generally at 16, arranged in substantially equally-spaced relationship longitudinally of the web and in a substantially-straight line coinciding with the longitudinal axis thereof, each boss being substantially-rectangular and preferably square in outline, as shown especially well in Fig. 1.

The web 15 comprises preferably an upper ply 17 and a lower ply 18 held together by a single set of binder warp strands, as indicated at 19. Although a single set of binder warp strands has been found satisfactory, it will be understood that two or more sets of binders may be used. Referring to Fig. 5, the lower ply 18 comprises

warps or ends 20 interwoven with picks of weft strands 21, the particular form of weave employed in the ply illustrated being what is commonly referred to as a plain or basket weave, each warp or end 20 comprising preferably a double strand or thread, as shown especially well in Fig. 6, woven with its warp floats extending alternately over and under the single weft strands 21.

The upper ply 17 comprises essentially a plain weave consisting of double stranded warps 22 (see Fig. 6) interwoven with picks of weft strands 23. More particularly, however, the continuity of the weaving of the upper ply is interrupted both in a direction transverse to the length of the web and in the direction of its longitudinal axis, as illustrated by the pick schedule of Fig. 7, for forming the segregated integrally-woven bosses 16 of the upper ply in accordance with the improved method of this invention. For the purpose of clarity, the warps of the lower ply have been omitted from Fig. 7, and the upper ply of the woven web, as represented by the pick schedule of Fig. 7, may be considered as constituting a center section A in which the weaving of the fabric is continuous; and outer sections B—B on opposite sides respectively of the center section A, in each of which outer sections the weaving is interrupted, the woven areas C—C of the respective outer sections B—B of the upper ply being substantially opposite each other and on opposite sides respectively of those areas D of the center section A which form the bosses 16 of the fabric, in the manner described below.

Each boss 16 of the upper ply constitutes an integral woven part thereof of a predetermined height which, in the present embodiment, corresponds substantially to the thickness of the two-ply web as illustrated especially well in Figs. 3 and 4. More particularly, each boss 16 constitutes a plurality of upstanding loops 24 of a woven single-ply fabric formed from the section D of the upper ply 17, the preferred number of loops 24 for forming a single boss 16 being four. Each loop 24 comprises a short length of woven fabric consisting of five picks of weft strands 23 identified by the picks e, f, g, h, and j in the upper ply of the web, as indicated in Fig. 7, interwoven with double-stranded warps 22 and corresponding in width to the width of the section A of the fabric. As deduced from the pick schedule of Fig. 7, each fabric loop is tied at its opposite base termini respectively into the upper ply of the web by means of terminal strands ee and jj respectively which are continuous with the first and last picks e and j respectively of a loop, each terminal strand ee and jj extending across the fabric from one edge of the section A of the upper ply, to the corresponding outer edge of the web. The terminal strand jj of each loop is continuous with the weft k of the subsequent pick which is woven into the lower ply of the fabric across the full width thereof and which reappears in the upper ply of the two-ply fabric on the next pick as indicated at m. The weft m crosses the full width of the upper ply and on the next-succeeding pick is woven into the lower ply of the fabric the full width thereof as indicated at n and reappears on the top ply of the fabric on the next-succeeding pick as the terminal strand ee of the next-succeeding loop.

In accordance with the method of this invention, each woven boss 16 is formed during the continuous weaving of the two-ply web by the pick schedule of Fig. 7, from which it will be clear that by shedding the sets of warp threads 22 of the

center section A of the upper ply, for five successive picks of the weft, including the warps in sections B—B for only the first and last picks, and then shedding the warp threads of the two-ply fabric in sequence for the following three picks, a short length of single-ply fabric herein-after referred to as a "loop fabric" is formed, the terminal strands of which are fastened into the lower ply of the fabric by the two wefts k and n respectively and into the upper ply by the single weft m and the terminal strands ee and jj. Consequently, the packing of these three consecutive wefts of the two-ply fabric by the loom-batten causes the single-ply woven loop fabric to arch or form a loop 24 upstanding from the upper ply of the web. By repeating this pick schedule for four successive times, four loops 24 will be formed to complete the construction of one integrally-woven boss 16 of the upper ply, the width 10 of the boss corresponding substantially to the width of the section A of the fabric. The length 15 of the boss is determined primarily by the compactness of the juxtaposed loops and the number of loops and, in this instance, corresponds substantially to the width of the boss.

Although four loops have been found adequate to form a single boss, it will be appreciated that the number of loops used may be more or less than four, depending upon such factors as the required size of the boss, the kind of materials, the purpose for which the boss is to be used, and similar considerations. As explained above, the bosses of a spring-liner fabric are adapted to engage in apertures of the upper leaf of a pair of superposed 20 spring leaves to hold the liner-fabric in place therebetween, and hence, the spring-liner fabric is formed preferably of relatively-heavy cotton strands or equivalent material, so as to provide stiff substantially-rigid bosses having a high resistance to deformation, wear and shearing.

Fig. 10 shows one application of the spring-liner fabric of this invention to a spring 25, the superposed leaves 26 of the spring being supported in vertically-spaced relationship by fabric 27 spring-liner members or pads 27 such as illustrated in Figs. 8 and 9, these pads 27 being formed by cutting off from a continuous length of the embossed spring-liner fabric 15, a substantially-square piece of material having a boss 16 at substantially its geometric center. For optimum performance, this square pad 27, including its boss 16, is then impregnated with paraffin wax or an equivalent material, whereupon a die is brought down onto the boss to round-over its corners and upper edges in the manner indicated in Figs. 8 and 9, so that the boss will readily fit into a round aperture 28 adjacent the outer end of a spring leaf, thereby to retain the pad in place. It will be understood, however, that these subsequent operations of impregnating the embossed pads and shaping the bosses thereof, are not subject-matters of the present invention.

The showing of Fig. 11

65 In the showing of Fig. 11 certain of the parts correspond to those previously described herein and such parts have reference characters applied thereto which correspond to those previously employed.

A modification of the construction of the web 15 hereinabove described, is shown in Fig. 11 and is substantially identical in all respects to the web 15 except for the configuration of the integrally-woven bosses thereof. The latter as indicated at 29, are woven so as to be more nearly

circular in shape and thereby fit more readily into a circular aperture of a spring leaf, and to this end, the operation of the harnesses is modified so that the first and last loops 30—30 of each boss 29 are made shorter, in a transverse direction, than the two intermediate loops 31—31. Thus, the substantially-square corners which characterize the bosses 16 of the spring-liner web 15, are eliminated, with the result that the bosses 29 may be made to conform more readily to the circular apertures of the leaf springs.

The showing of Figs. 12, 13 and 14

Inasmuch as certain of the parts shown in Figs. 12, 13 and 14 now to be described are similar to parts previously described, certain of the parts shown therein have similar reference characters applied thereto plus the subscript "a."

The spring-liner web 15a shown schematically in Figs. 12 and 13 is a modification of the web shown in Figs. 1 through 6, and is substantially identical thereto in all respects except that some of the warps or ends 22a and 26a respectively of the upper and lower plies of the fabric comprise wire strands. More particularly, alternate pairs of warps or ends comprise a plurality or set of wire strands which consist, preferably, of brass or an equivalent metal. As shown in detail in Fig. 14, each set of wire strands, herein-after referred to as "wire ends," comprises preferably six untwisted bunched wires woven into the fabric in substantially-parallel relationship. Figs. 12 and 13 show especially well the characteristically novel weave of the fabric wherein the wire ends 32 of the lower ply 18a are woven into the fabric across the full width thereof, whereas, the wire ends 33 of the upper ply 17a are included only in those portions of the fabric corresponding to the sections B—B shown in the pick schedule of Fig. 7; that is to say, the wire ends or warps 31 are not included in the section A of the fabric from which the bosses are formed.

The inclusion of wire ends in the spring-liner fabric in the manner hereinabove described, has been found to increase the durability and stiffness of the fabric and—what is more important—from the standpoint of its use as a spring-liner material, to make the fabric relatively incompressible. Thus, spring-liner pads cut from the spring-liner web 15a will retain their shape over relatively-long periods of use.

Although the spring-liners have been described and illustrated as comprising individual embossed pads adapted to be inserted between superposed spring leaves, it is within the purview of the invention to form a spring-liner as a continuous length of woven webbing provided with a pair of integrally-woven bosses arranged at opposite ends thereof respectively, so as to engage in the corresponding apertures at opposite ends of a spring leaf; or in a broader sense, the spacing of the bosses longitudinally of a woven spring-liner fabric may vary, depending upon the particular form in which the spring-liner fabric is to be made.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 15 said loop being spaced back a substantial distance from the adjacent edge of the fabric; and the warp portions of each two adjacent base ends of each two adjacent loops being woven directly to the same pick, which said pick extends substantially the width of the fabric.
2. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 25 said loop being spaced back a substantial distance from the adjacent edge of the fabric; and the warp portions of each of the two base ends of each loop, being respectively woven directly to a corresponding one of two successive picks which extend substantially the width of the fabric.
3. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 35 said loop being spaced back a substantial distance from the adjacent edge of the fabric; and the warp portions of each of the two base ends of each loop, being respectively woven directly to a corresponding one of two successive picks which extend substantially the width of the fabric.
4. A spring-liner for use between the leaves of a leaf spring, and comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 45 said loop being spaced back a substantial distance from the adjacent edge of the fabric; and the warp portions of each of the two base ends of each loop, being respectively woven directly to a corresponding one of two successive picks which extend substantially the width of the fabric.
5. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 55 said loop being spaced back a substantial distance from the adjacent edge of the fabric; and the warp portions of each of the two base ends of each loop, being respectively woven directly to a corresponding one of two successive picks which extend substantially the width of the fabric.
6. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 65 said loop being spaced back a substantial distance from the adjacent edge of the fabric; and the warp portions of each of the two base ends of each loop, being respectively woven directly to a corresponding one of two successive picks which extend substantially the width of the fabric.
7. A spring-liner for use between the leaves of a leaf spring, and comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each 75 said loop being spaced back a substantial distance from the adjacent edge of the fabric; and the warp portions of each of the two base ends of each loop, being respectively woven directly to a corresponding one of two successive picks which extend substantially the width of the fabric.

gated loop with the picks extending in the direction of length of the loop, and each end of each said loop being spaced back a substantial distance from the adjacent edge of the fabric; and binder strands connecting the bottom portion of said boss at a plurality of locations substantially inwardly away from the edges of the boss, to said lower ply.

5. A spring-liner for use between the leaves of a leaf spring, and comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric; and binder strands connecting the bottom portion of said boss at a plurality of locations substantially inwardly away from the edges of the boss, to said lower ply.

6. A spring-liner for use between the leaves of a leaf spring, and comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each of the two base ends of each loop, being respectively woven directly to a corresponding one of two successive picks which extend substantially the width of the fabric; and binder strands connecting the bottom portion of said boss at a plurality of locations substantially inwardly away from the edges of the boss, to said lower ply.

7. A spring-liner for use between the leaves of a leaf spring, and comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric; and the warp

portions of each of the two base ends of each loop, being respectively woven directly to a corresponding one of two successive picks which extend substantially the width of the fabric; and binder strands connecting the bottom portion of said boss at a plurality of locations substantially inwardly away from the edges of the boss, to said lower ply.

8. A leaf spring having a plurality of superposed leaves, each of a plurality of which leaves has apertures; and a plurality of spring-liners each having a boss; each said spring-liner being located between two of said superposed leaves and with its boss extending into a said aperture; and each said spring-liner comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric.

9. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric.

10. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each of the two base ends of each loop, being respectively woven directly to

a corresponding one of two successive picks which extend substantially the width of the fabric.

11. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric; and the warp portions of each of the two base ends of each loop, being respectively woven directly to a corresponding one of two successive picks which extend substantially the width of the fabric.

12. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and binder strands connecting the bottom portion of said boss at a plurality of locations substantially inwardly away from the edges of the boss, to said lower ply.

13. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance

from the adjacent edges of the fabric; and the warp portions of each two adjacent base ends of each two adjacent loops being woven directly to the same pick, which said pick extends substantially the width of the fabric; and binder strands connecting the bottom portion of said boss at a plurality of locations substantially inwardly away from the edges of the boss, to said lower ply.

14. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each of the two base ends of each loop, being respectively woven directly to a corresponding one of two successive picks which extend substantially the width of the fabric; and binder strands connecting the bottom portion of said boss at a plurality of locations substantially inwardly away from the edges of the boss, to said lower ply.

15. A leaf spring having a plurality of superposed leaves, each of a plurality of said leaves having apertures; and a plurality of spring-liners each having a boss; each said spring-liner being located between two superposed leaves and with its boss extending into a said aperture; and each said spring-liner comprising: a plurality of warps woven with a plurality of picks to form a woven fabric embodying an upper ply and a lower ply, and having a woven boss woven integrally with, and projecting upwardly from one face of, said fabric; said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric; and the warp portions of each of the two base ends of each loop, being respectively woven directly to a corresponding one of two successive picks which extend substantially the width of the fabric; and binder strands connecting the bottom portion of said boss at a plurality of locations substantially inwardly away from the edges of the boss, to said lower ply.

16. A fabric for forming spring-liners for use between the leaves of a leaf spring, and comprising: a plurality of warps woven with a plurality of picks to form a woven fabric embodying

an upper ply and a lower ply, and having a plurality of integral woven bosses spaced apart along, and woven integrally with, and projecting upwardly from one face of, said fabric; each said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and binder strands connecting the bottom portion of each said boss at a plurality of locations substantially inwardly away from the edges of each boss, to said lower ply.

17. A fabric for forming spring-liners for use between the leaves of a leaf spring, and comprising: a plurality of warps woven with a plurality of picks to form a woven fabric embodying an upper ply and a lower ply, and having a plurality of integral woven bosses spaced apart along, and woven integrally with, and projecting upwardly from one face of, said fabric; each said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a substantial distance from the adjacent edge of the fabric; and the warp portions of each two adjacent base ends of each two adjacent loops being woven directly to the same pick, which said pick extends substantially the width of the fabric; and binder strands connecting the bottom portion of each said boss at a plurality of locations substantially inwardly away from the edges of each boss, to said lower ply.

18. A fabric for forming spring-liners for use between the leaves of a leaf spring, and comprising: a plurality of warps woven with a plurality of picks to form a woven fabric embodying an upper ply and a lower ply, and having a plurality of integral woven bosses spaced apart along, and woven integrally with, and projecting upwardly from one face of, said fabric; each said boss comprising a plurality of integrally woven, successive, parallel loops adjacent to one another and projecting upwardly from said one face of said fabric; and each said woven loop comprising a plurality of warps woven with a plurality of picks to form an elongated loop with the picks extending in the direction of length of the loop, and each end of each said loop being spaced back a

substantial distance from the adjacent edge of the fabric; and the warp portions of each of the two base ends of each loop, being respectively woven directly to a corresponding one of two successive picks which extend substantially the width of the fabric; and binder strands connecting the bottom portion of each said boss at a plurality of locations substantially inwardly away from the edges of each boss, to said lower ply.

19. A liner for use between the leaves of a leaf spring, said liner comprising: a two-ply fabric member of interwoven textile and metallic strands; and a fabric boss woven on one face of said fabric member, said fabric boss comprising a plurality of upstanding loops extending transversely of the warp strands of said fabric member, each of said loops being a single-ply woven fabric consisting of textile strands only interwoven with one ply of said woven-fabric member and in immediate juxtaposition to each other, the opposite ends of each fabric loop being equally spaced from the corresponding edges of said fabric member.

20. A fabric for forming spring-liners, said fabric comprising: a fabric web woven of textile and metallic strands and substantially equal in width to the width of a leaf spring, said web embodying an upper ply and a lower ply; and a plurality of bosses arranged in longitudinally spaced relationship on one face of said woven-fabric web, each boss comprising a plurality of juxtaposed woven loops extending transversely of the warp strands of said fabric web and interwoven with the upper ply thereof in immediate juxtaposition to each other, the opposite ends of each fabric loop of the web being substantially equally spaced from the corresponding edges of said fabric web.
